TUBE BENDER

Richard V. Strybel, Elk Grove Village, Ill., assignor to Imperial-Eastman Corporation, a corporation of Illinois
Filed May 21, 1962, Ser. No. 196,102
7 Claims. (Cl. 72—459)

This invention relates to tube benders and in particular to manually operable tube benders.

In one well-known form of manually operable tube bender, a shoe element is pivotally connected to a mandrel to move along a peripheral groove in the mandrel and in so moving press a tube into the groove to effect a desired bend therein. Conventionally, a first handle is secured to the mandrel and a second handle is secured to the shoe, permitting the user, by suitable manipulation of the handles, to the effect the desired relative movement between the shoe and the mandrel. In the starting position, it is desirable to have the two handles extend generally perpendicular to each other to permit maximum effort to be exerted by the user. This, however, has the disadvantage of causing the handles to cross where the bend is continued beyond 90°. The present invention comprehends an improved arrangement of the tube bender structure whereby the crossing of the handles is effectively eliminated.

Thus, a principal object of the present invention is the provision of a new and improved tube bender.

Another object of the invention is the provision of such a tube bender having new and improved means for associating the shoe with the mandrel to permit selective positioning of the shoe in tube bending association with the mandrel with the shoe handle being disposed in either of two substantially perpendicular arrangements. Thus, the shoe may be repositioned upon the completion of a 90° bend so as to reposition the shoe handle in a direction away from the mandrel handle to permit a subsequent additional 90° bend in the tube without a crossing of the shoe and mandrel handles.

A further object of the invention is to provision of such a tube bender wherein the shoe is connected to the mandrel by a link having an inner end pivotally carried by the mandrel, the link having an outer end provided with a first shoulder, and the shoe being provided with a pair of shoulders for selective engagement with the link shoulder for releasably retaining the shoe in either of two preselected positions.

Other features and advantages will become apparent from the following detailed description taken in connection with the accompanying drawings wherein:

FIG. 1 is a fragmentary elevation of a tube bender embodying the invention with the shoe illustrated in full lines as at the start of a tube bending operation and in dashed lines as upon completion of a 90° bend in the tube;

FIG. 2 is a section taken substantially along the line 2—2 of FIG. 1;

FIG. 3 is a side view of the tube bender looking from the top of FIG. 1; and

FIG. 4 is a fragmentary elevation of the tube bender with the shoe shown in full lines as repositioned to commence an additional 90° bending operation in dot-dashed lines as during such repositioning, and in dashed lines as upon completion of a 180° bend.

In the exemplary embodiment of the invention as disclosed in the drawing, a tube bender generally designated 10 is shown to include a conventional mandrel 11 having a peripheral tube bending groove 12 extending annularly concentrically of an axis 13 through the center of the mandrel. A first handle 14 is secured to the mandrel as by screws 15 and a conventional hook 16 is secured to

the mandrel adjacent handle 14 as by screw 17. The hook is arranged in the conventional manner to engage a portion of the tube T to be bend in the tube bender and retain the tube against movement during the tube-bending operation.

The tube bender further includes a bending shoe 18 to which is secured a second handle 19. The bending shoe is connected to the mandrel by a link 20 having an inner end 21 connected to the mandrel by a pivot 22 permitting the link to swing about the axis 13 as shown in FIGS. 1 and 4. The outer end 23 of the link 20 is provided with a pivot post 24 extending through an elongated slot 25 in the shoe 18 to pivotally connect the shoe to the link.

As indicated briefly above, the shoe 18 may be selectively retained on the link 20 in either of two generally perpendicularly related positions. To this end the link is provided with a projection 26 defining a shoulder 27. The projection extends from the link generally parallel to the axis 13 and the shoulder faces toward the inner end 21 of the link. Shoe 18 is provided with a first tube-engaging surface 28 defined by a rectilinear groove, and a second tube-engaging surface 29 defined by a second rectilinear groove perpendicularly intersecting the first groove 28. As best seen in FIG. 1, groove 28 extends generally parallel to the direction of elongation of slot 25 and groove 29 extends perpendicular thereto.

As shown in FIG. 1, the shoe 18 is provided with a pair of shoulders 30 and 31 for selective engagement with the shoulder 27 of the link 20 to retain the shoe selectively in the position of FIG. 1 (full lines) and the position of FIG. 4 (dotted lines). More specifically, shoulder 30 is defined by a notch 32 in the portion of the shoe defining groove 29 and shoulder 31 is defined by a notch 33 in the portion of the shoe opposite the portion defining groove 28. Thus, when shoulder 30 engages shoulder 27, as shown in FIG. 1, groove 28 confronts mandrel groove 12 whereby movement of the shoe from the full line position of FIG. 1 to the dashed line position of FIG. 1 effects a 90° bend in the tube T.

As can be seen from the dotted line position of handle 19 in FIG. 1, further movement thereof in a clockwise direction about the axis 13 would tend to cause the handle 19 to cross the handle 14. To preclude this, the shoe is repositioned as shown in FIG. 4 so as to bring handle 19 back to a position wherein it extends substantially perpendicularly to the handle 14 permitting an additional 90° bend to be formed in the tube T as shown in FIG. 4 without a crossing of the handles. The repositioning of the shoe is effected by simply pivoting the shoe from the position shown in dashed lines in FIG. 1 to the position shown in dot-dash lines in FIG. 4 and then sliding the shoe on the link 20 toward the axis 13 until the post is received in the opposite end of the elongated slot 25 permitting the second shoulder 31 to engage the link shoulder 27. Handle 19 may then be manipulated to swing the shoe on link 20 from the full line position of FIG. 4 to the dashed line position at the bottom of the figure to complete the 180° bend in the tube T.

The shoe may be readily released from the tube at the 90° position by simply pivoting the shoe in a counterclockwise direction about the post 24 and may be readily spaced from the tube in the 180° position by pivoting the shoe slightly in a counterclockwise direction to disengage the shoulder 31 from the link shoulder 27 and permit the shoe to be slid outwardly along the link 20 away from the mandrel.

As shown in FIG. 1, the recesses 32 and 33 are generally triangular and the projection 26 is complementarily triangular so as to be received in the recesses in the two different tube-bending positions of the shoe. The projection 26

3

may be made sturdy so as to hold the shoe against the tube-bending forces generated in the bending operation. Thus, tube bender 10 provides a strong maintenance-free arrangement permitting facilitated selected positioning of the shoe so that the user may effect a full 180° bend of the tube by manipulation of the two handles through the same 90° quadrant, effectively eliminating the need for crossing of the handles at any time.

While I have shown and described one embodiment of my invention, it is to be understood that it is capable of many modifications. Changes, therefore, in the construction and arrangement may be made without departing from the spirit and scope of the invention as defined in the appended claims.

I claim:

1. In a tube bender having a mandrel provided with an axis, a peripheral tube-bending groove annularly concentric of said axis, an elongated handle secured to the mandrel, and means for retaining a tube in association with the mandrel groove, means for bending the tube into the groove comprising: a connector link having an inner end and an outer end; means connecting the inner end of the link to said mandrel to pivot about said axis; a bending shoe having a first tube engaging surface and a second tube-engaging surface extending angularly to said first tube-engaging surface, and tube-engaging surfaces having the same radius of curvature in a cross section; means connecting the shoe to said outer end of the link for pivoting about an axis parallel to said mandrel axis; an elongated handle secured to the shoe; a first shoulder on said link; a second shoulder on said shoe engaging said first shoulder when said shoe is pivoted on the link to a first position wherein said first tube-engaging surface is juxtaposed to said mandrel groove; and a third shoulder on said shoe engaging said first shoulder when said shoe is pivoted on the link to a second position wherein said second tube-engaging surface is juxtaposed to said mandrel groove.

2. The tube bender of claim 1 wherein said means connecting the shoe to the link comprises a post on one of said shoe and said link and an elongated groove on the other of said shoe and said link slidably receiving said post.

3. The tube bender of claim 1 wherein said tube-en-

gaging surfaces are defined by intersecting rectilinear grooves in the shoe.

4. The tube bender of claim 1 wherein said tube-engaging surfaces are defined by intersecting rectilinear grooves in the shoe and one of said shoulders is formed in the portion of the shoe defining one of said grooves.

5. In a tube bender having a mandrel provided with an axis, a peripheral tube-bending groove annularly concentric of said axis, an elongated handle secured to the mandrel, and means for retaining a tube in association with the mandrel groove, means for bending the tube into the groove comprising: a connector link having an inner end and an outer end; means connecting the inner end of the link to said mandrel to pivot about said axis; a bending shoe having a first tube-engaging surface and a second tube-engaging surface extending substantially perpendicularly to said first tube-engaging surface; means connecting the shoe to said outer end of the link for pivoting about an axis parallel to said mandrel axis; an elongated handle secured to the shoe; a first shoulder on said outer end of the link facing toward said inner end; a second shoulder of said shoe extending parallel to said first tube-engaging surface, said second shoulder engaging said first shoulder when said shoe is pivoted on the link to the first position wherein said first tube-engaging surface is juxtaposed to said mandrel groove; and a third shoulder on said shoe extending parallel to said second tube-engaging surface, said third shoulder engaging said first shoulder when said shoe is pivoted on the link to a second position wherein said second tube-engaging surface is juxtaposed to said mandrel groove.

6. The tube bender of claim 5 wherein said first shoulder projects from the link parallel to said axes.

7. The tube bender of claim 5 wherein said shoe is provided with a recess adjacent said second shoulder to receive said first shoulder when said shoe is in said first position.
